UNITED STATES PATENT OFFICE.

EDWIN R. ESTEP, OF DETROIT, MICHIGAN, ASSIGNOR, BY MESNE ASSIGNMENTS, TO
PACKARD MOTOR CAR COMPANY, OF DETROIT, MICHIGAN, A CORPORATION OF
MICHIGAN.

DESIGN FOR A LAMP-CASING.

42,127.

Specification for Design.

Patented Feb. 6, 1912.

Application filed November 21, 1908. Serial No. 463,925. Term of patent 7 years.

To all whom it may concern:

Be it known that I, EDWIN R. ESTEP, a citizen of the United States, residing at Detroit, in the county of Wayne and State of Michigan, have invented a new, original, and ornamental Design for Lamp-Casings, of which the following is a specification, reference being had to the accompanying drawing, forming part thereof.

The figure is a perspective view of a lamp casing showing my new design.

As shown in the drawing my design is made up of four similar panels joined edge

to edge, each panel having a peculiar and ornamental shape and outline, and the lamp as a whole tapering upwardly. Each of the panels contains a central transparent portion, and it will be understood that the light itself is to be surrounded by these panels.

I claim:

The ornamental design for a lamp casing, as shown, and described.

EDWIN R. ESTEP.
